UNITED STATES PATENT OFFICE.

STEWART HARTSHORN, OF MILLBURN, NEW JERSEY.

SPRING SHADE-ROLLER.

SPECIFICATION forming part of Letters Patent No. 320,247, dated June 16, 1885.

Application filed August 6, 1884. (No model.)

To all whom it may concern:

Be it known that I, STEWART HARTSHORN, residing in Millburn, in the county of Essex in the State of New Jersey, have invented a 5 certain new and useful Improvement in Spring Shade-Rollers, of which the following is a full, clear, and exact description, reference being had to the accompanying drawings, making a part of this specification.

10 My invention relates to a new and improved mode of attaching the end plate or disk on which the pawls or their equivalents are usually mounted to the roller; and also refers to a ready and effective means of securing the 15 outer end of the spring to the end plate.

In the drawings illustrating my improvements, in which like letters indicate like parts, Figure 1 is a view of a roller, showing the end 20 plate fastened to the same by my improved method, a part of the roller being broken away to show the mode of attachment. Fig. 2 is a detached view of the end plate, showing the screw-collar by which it is attached to the roller. Fig. 3 is a view of the end plate, the 25 spindle connected with the same, and the spring mounted upon the latter and secured at its outer end to the end plate by means of the screw on the collar of the latter. Fig. 4 is a view of a modified construction of the end 30 plate, showing an outer collar or ring to prevent the roller splitting.

My invention consists in a novel method of 35 constructing the end plate or disk by which it can be readily and quickly attached directly to the roller, and held firmly secured thereto without the use of any separate means of fastening, as nails, screws, or a retaining-cap or ferrule frequently employed for this purpose.

40 In my improved method of construction, the end plate is provided on its inner face with a collar or ring, C, either cast or formed with the plate, or made separate and attached to the same. This collar is of such a diameter compared with the diameter of the bore in the roller that it will enter the roller and permit the end plate to fit closely against the end of the latter, as will be seen in Fig. 1. On the outside of this collar is formed a screw, as 45 shown in the drawings, the thread of which

is such that when the collar is inserted in the bore, and the end plate turned, the screw will bite into or enter the wood of the roller. This screw may be cast with the collar, or may be cut in the latter, or formed in any manner 55 found convenient, and instead of being continuous around the collar the screw may be formed by a series of detached threads or segments or projections. When the thread is to be cut or formed on the collar after the latter is made, the diameter of the collar should be a little greater than that of the bore of the roller, so the screw will enter and take hold 60 of the wood. The end plate thus constructed is attached to the roller by simply screwing 65 the collar into the bore of the latter, when it will be firmly and securely held without any other fastening.

The connection of the spindle with the end 70 plate, and attachment of the spring to the spindle and to the end plate or roller, and the arrangement of the spindle and spring within the roller, may be by any of the methods now in use with the ordinary construction of end plates. The outer end of the spring, when the 75 inner end is fastened to the spindle, may be connected to the end plate in any manner, and the end plate, spindle, and spring mounted thereon may all be united together, as is shown in Fig. 3, and connected with the roller 80 by simply inserting the spindle and spring within the bore, and screwing the collar on the end plate into the latter. Thus, by my improvement, I provide on the end plate itself a ready and effective method of attaching the 85 plate to the roller, and avoid all the trouble and annoyance caused by the use of nails or screws to fasten the plate, and do away with the use of a ferrule or cap on the end of the roller for this purpose; and, moreover, by my 90 improved method of fastening, the end plate cannot become detached from the roller while in use, as frequently happens with the mode of attachment now employed, and yet, if occasion requires, the plate can be readily removed from the roller without injuring the latter.

To prevent the end of the roller splitting when the collar is screwed into the bore of the same, an outer collar or ring (shown at R, 95 100

Fig. 4,) may be formed on the edge of the inner face of the disk or plate, so as to surround or fit over the end of the roller, and protect the same from injury.

5 My improved construction of end plate also furnishes a ready and secure method of attaching the outer end of the spring to the end plate and roller.

By forming the screw-threads on the collar 10 a little deeper than is required for taking into the wood of the roller, the end of the spring may be made to enter the threads by simply turning the screw collar into the end of the coil, as is shown in Fig. 3, and the spring is thus 15 firmly and securely fastened to the end plate; but the use of the screw-threads for attaching the end plate to the roller is not interfered with or affected. By this method of securing the spring, the latter can be used just as it 20 comes from or leaves the mandrel, without any manipulation or preparation whatever.

I am aware that a cap carrying the roller-bearing or a shell has been attached to the

roller by a screw-thread formed on the inside surface of such cap; and also that the spring 25 has been attached to the end plate by means of a smooth or unthreaded collar, as shown in Letters Patent granted to me February 19, 1884, and numbered 293,871.

What is claimed as new is—

1. In a spring shade-roller, the combination, with the roller, of the end plate having a screw-thread collar centrally thereon for entering the bore of the roller, substantially as and for the purpose described. 30

2. In spring shade-rollers, the combination, with the roller, of the end plate having a central screw-collar for attaching the same to the roller and spindle and spring, the latter being attached by its inner end to the spindle and 40 by its outer end to the end plate by the screw-thread on the collar. 35

STEWART HARTSHORN.
